CAM LOCKS FOR ZIPPER FASTENERS

Osborne Firing, Woodbury, and Otto J. Huelster, Plymouth, Conn., assignors to Scovill Manufacturing Company, Waterbury, Conn., a corporation of Connecticut

Application April 18, 1956, Serial No. 579,015

3 Claims. (Cl. 24—205.14)

This invention relates to improvements in cam locks for zipper fasteners and to a novel method of making the same.

For reasons well understood in the art, such garments as men's trousers are provided with cam lock sliders as distinguished from other forms such as the pin lock or automatic lock. Ever since the introduction of cam lock sliders for trousers many years ago there has been a serious problem having to do with what is called in the trade as "reverse pressing." The condition comes about when a garment is laundered or dry cleaned because it may come to the pressing machine with the pull tab laid backward or in the reverse or unlocking position. The cam or cams thus project upwardly and are subjected to extreme pressure by the pressing machine. This very frequently results in a deformation of the cam itself, or a bending of the bifurcations of the pull tab, so that when the pull is swung to locking position the cam or cams will not engage the fastener elements with sufficient pressure to lock the slider.

Many attempts have been made to solve this problem as indicated by several patents in this particular art, but in actual experience none of them have been wholly satisfactory.

The problem is further intensified because of the cost factor involved. It is desirable for this reason to make the pull tab from a flat strip of metal no wider than the rectangular handle portion of the tab so that the cams themselves must be formed from longitudinal extensions of this same metal. The necessary height of the cam is substantially more than the thickness of the metal itself so that when the cams are formed by folding over tongues extending from the end of the tab, at least some part of the cam would be spaced from the body of the pull tab. This is exemplified in Patent No. 2,539,520, granted January 30, 1951. It is also desirable that the cams have a considerable extent lengthwise of the pull tab to avoid too great concentration of force from the pressing machine. For this reason among others it would not suffice merely to make a sharp U bend of the tongue with its end against the body of the pull tab.

According to our invention, after making provision for sufficient metal in the tongues from which the cams are to be formed, the folded over tongues are subjected to a lateral swaging operation which produces a solid body of metal which is of sufficient height and length for the cam, and at the same time is supported by direct contact with the body of the pull tab throughout the length of the cam. Obviously this results in a cam which will withstand much greater pressure than those of the cam locks described above.

The detailed nature of the improvement and the method by which it is accomplished will be apparent from the following description taken in conjunction with the accompanying drawings in which:

Fig. 1 is a perspective view of a zipper slider having a pull tab embodying our invention attached thereto and shown in unlocked position.

2

Fig. 2 is a longitudinal sectional view through the slider showing the pull tab in element gripping position, with dotted lines indicating the reverse position.

Figs. 3, 4 and 5 are perspective views of the pull tab showing different stages in forming the locking cams.

Fig. 6 shows portions of the forming tools for swaging the cam lugs of the pull tab as they appear prior to the swaging operation.

Fig. 7 is a similar view showing the tools in final swaging position.

Fig. 8 is a perspective view of one of the die members and swaging tools in separated relationship, and

Fig. 9 is a perspective view of the pull tab showing the bifurcated end as it appears before the assembly of the slider.

Referring now to the drawings in which like numerals designate like parts throughout the several views, the numeral 10 refers generally to a slider having upper and lower spaced wings 11 and 12 secured together at one end by an integral neck 13. The upper wing is provided with a pair of parallel slots 14 between which is formed a bail or lug 15 to which a pull tab 16 is attached for operating the slider. The pull tab 16 is formed with a pair of identical cams 17 that are adapted to extend through the slots 14 when the pull tab is in locked position as shown in Fig. 2 and pressed against the adjacent surface of the zipper elements 18 on a stringer 19 of the conventional type. The inner surface of the lower wing is formed with a depression 20 into which the elements 18 are forced to lock the slider against movement on the stringers.

The particular construction forming the cams 17 on the pull tab forms the subject of this invention. One of the first stages in the manufacture of the pull tab is to stamp out the blank 16a as shown in Fig. 3 wherein at one end of the blank 16a is a half round opening 21 for convenience in operating the tab. The opposite end of the blank 16a is bifurcated because of the polygonal shaped opening 22 and slot 23 extending through the end of the blank 16a, the shape of the opening 22 and the slot 23 being of such character as to provide inwardly directed opposed trunnions 24. The blank 16a is formed with integral tongues 25 extending from the end of said blank on opposite sides of the slot 23, the inner edges 26 of the lugs being diverging relative to the longitudinal axis of said blank. The outside edges 27 of said tongues 25 are in line with the longitudinal edges of said blank except for the cutout recesses 28.

The next step of the operation is shown in Fig. 4 where the tongues 25 are bent over to lie adjacent the upper surface of the blank 16a with the tongue ends positioned relatively close to or in contact with said surface. It is to be noted that in bending the tongues 25 from the position shown in Fig. 3 to the position shown in Fig. 4, the outer edges 27 will remain in a plane common with the outer edges of the blank 16a.

The manner in which the tongues 25 are reformed to provide the solid cams is shown in Figs. 6 and 7. In this step the blank 16a, as shown in the Fig. 4 state, is conveyed to a support plate 30, and an anvil block 31 is positioned between the adjacent surfaces 26 of the tongues 25. A pair of swaging tools 32 are suitably mounted to reciprocally slide from opposite sides of the blank 16a in direct line with the tongues 25. The leading end of the tools 32 has a blunt face 33 and a projection 34 having a tapered edge surface on all sides except the bottom of about 15 degrees. The upper edge of the projection is inclined lengthwise thereof on an angle substantially comparable to the position that the cams assume when formed as shown in Fig. 4 and this upper edge reaches up to about one-half the thickness of said tongues. During the swaging operation it

is necessary to confine the outer surfaces of the tongues 25. For this purpose die members 35 are provided that descend against the top of the pull tab 16 along with the anvil block 31. Each die member is formed with a transverse recess 36 shaped to conform to the cam 17 and it is within this recess that the swaging tool 32 reciprocates during the swaging operation.

As the tools 32 operate on their inward stroke the projection 34 first strikes against a portion of the outer edges of the wall 27 and swage the contacted portion inwardly. Also the blunt face 33 of the tools 32 will abut the remaining faces of the edges 27 that are not contacted by the tool projection 34 and force the remaining portion of said edges 27 inwardly to a position substantially flush with the base of the cutout recess 28. All the stock of the lugs that is forced inwardly by the end projection 34 as well as the blunt edge 33 of the swaging tools 32 will be drifted downward toward the adjacent surface of the blank 16a and produce a reenforcing wall 37. The stock that is drifted by the swaging operation is sufficient to close up the space between the cams 17 and blank 16a and cause the wall 37 to lie in direct contact with the adjacent surface of the blank 16a.

During the lateral swaging operation the wide portions of the bent-over tongues are reduced to provide cams 17 of uniform width which are set inwardly from the side edge of the pull tab. Thus, in the reverse position of the pull tab there is a solid portion of the tab adjacent each cam that is in supporting contact with the slider body.

It will be observed although the cams are long enough to extend a substantial distance to each side of said trunnions they taper somewhat toward their inner ends so that the high point of each cam is slightly beyond the trunnions. This insures that the pull tab will not accidentally kick out of locked position.

After the swaging operation the ends of the blank 16a on opposite sides of the opening 22 and slot 23 including the trunnions 24 and the lugs 25 are spread apart to the position as shown in Fig. 8 for convenience in assembling the pull tab to the bail 15 of the slider 10.

It will be obvious that the reenforcing walls 37 will support the lugs 25 to prevent them from being crushed out of their normal position especially when the pull tab is in an unlocked position as shown in dotted outline in Fig. 2 and is subjected to any abnormal crushing force.

We claim:

1. A cam lock slider for zipper fasteners, a rectangular flat metal pull tab comprising a body portion having a central aperture adjacent one end so as to provide bifurcations at that end, each bifurcation having an inwardly extending trunnion by which the pull tab may be pivotally attached to a slider, at least one of said bifurcations having a longitudinal extension adjacent said end which has a U-bend beyond the body portion of the pull tab and which extension when bent, underlies the body portion of the pull tab on one side of said aperture, said extension projecting inwardly beyond the U-bend a substantial distance along the underside of the pull tab to form a locking cam whose height is substantially greater than the thickness of the metal of the pull tab, such cam having a laterally outwardly opening recess and a solid web of metal in supporting contact with the pull tab throughout the length of that portion of such cam which extends inwardly from the U-bend, such laterally opening recess and solid web of metal resulting from transverse swaging of the metal of said extension which underlies the pull tab.

2. A cam lock slider as set forth in claim 1 wherein each bifurcation has a longitudinal extension as recited and a cam as recited wherein each cam is located inwardly from the adjacent sides of the pull tab throughout the cam length.

3. A cam lock slider for zipper fasteners according to claim 1 wherein the cam is long enough to extend a substantial distance to each side of the adjacent trunnion, said cam tapering somewhat toward its inner end so that the high point of the cam is slightly beyond the said adjacent trunnion.
